UNITED STATES PATENT OFFICE.

HERMAN C. PROX, OF TERRE HAUTE, INDIANA, ASSIGNOR TO FRANK PROX COMPANY,
OF TERRE HAUTE, INDIANA, A CORPORATION OF INDIANA.

BOILER.

1,189,734.

Specification of Letters Patent.

Patented July 4, 1916.

Application filed December 19, 1914. Serial No. 878,032.

To all whom it may concern:

Be it known that I, HERMAN C. PROX, a citizen of the United States, residing at Terre Haute, in the county of Vigo and State 5 of Indiana, have invented a new and useful Boiler, of which the following is a specification.

My invention relates to boilers, and its object is to provide a boiler, and especially a 10 down-draft boiler, having a greater capacity for its size, having a more uniform steam-producing action, having an automatic shaking action, having an automatically controlled forced draft controlled in 15 common with a shaking grate, having a sectional construction whereby a broken part can be replaced without disturbing the remainder, and having water tubes both below and supporting the grate bars for the fuel 20 bed through which the down draft is obtained and at the bottom of the ash pit, so that the hottest parts of the flame may be effectively used, and having both a fuel chamber and flues below and above it, all of 25 which are totally surrounded by and separated from each other by water tubes.

In carrying out my invention in its preferred form, I provide a down-draft boiler the bed of fuel in which is supported by a 30 shaker grate which in turn rests on water tubes, so that the flame descending from the fuel bed strikes such water tubes, and I control this shaker grate automatically by the steam pressure. I also provide means for 35 producing a forced draft by forcing air into the fuel chamber above the fuel bed, so that the height of chimney required for the boiler may be reduced, and control this forced draft by the steam pressure, preferably operating it by the same mechanism which operates the shaker grate. I prefer to make the boiler sectional, with the water tubes which support the shaker grate bars forming 40 part of the sections, the main sections comprising outer substantially vertical water tubes or legs cross connected both at the top and bottom and at three intermediate points by water tubes, the water tube at the bottom forming the bottom of the ash pit, the next 45 higher forming the support for the shaker grate bar, and the highest three forming the walls for the horizontal flues and for separating the fuel chamber from such flues; and I combine with these main sections certain 50 other sections for directing the draft in the

desired channels; but in the broader aspects of my invention it is not essential that the water tubes supporting the grate bars form part of the sections or that they extend parallel to the sections.

The accompanying drawings illustrate my invention.

Figure 1 is a front elevation of a double boiler embodying my invention; Fig. 2 is a vertical sectional view through one of the 65 main or grate bar sections of such boiler; Fig. 3 is a partial plan view of the boiler shown in Fig. 1, to show the position of the controlling mechanism; and Fig. 4 is a side elevation of the boiler shown in Fig. 1, with 70 many of the parts broken away or in section.

The boiler illustrated is made in right and left parts, as clear from Fig. 1, each part in reality constituting a separate boiler and the two parts being mates. Each 75 part of this double boiler comprises a number of vertical transverse sections, of which there are five kinds: a front section 10, having an ash pit door 11 near the bottom, a common firing and draft door 12 near 80 the middle, and one or more flue cleaning doors 13 near the top, the various door openings being separated by transverse water tubes 14 and 15 connecting the vertical water legs 16, which are also connected 85 by transverse water tubes 17 and 18 at the bottom and the top; a series of main or grate bar sections 20 having these same vertical water legs 16, which in this case are cross connected by bottom and top water tubes 90 17 and 18 and an intermediate water tube 15 corresponding to those of the front section 10, with a water tube 21 parallel to and between the tubes 15 and 18, with vertical water tubes 22 interconnecting the 95 transverse water tubes 15, 21, and 18, and with transverse grate-bar-supporting water tubes 23 on about the same level with and behind the water tube 14 and vertically 100 between the transverse water tubes 17 and 15; a baffle plate section 25 having the same vertical water legs 16 and transverse water tubes 17, 18, and 21 as have the main or grate-bar sections 20 and also having a transverse water tube 26 which is of considerable vertical extent and reaches from 105 the level of the water tubes 23 to that of the water tubes 15 of the main sections; a vertical flue section 28 which is like the main or grate bar sections 20 save that the water 110

tubes 15 and 23 are omitted; and a rear section 30 which has the same water legs 16 as have the other sections, the same cross transverse water tubes 18 and 21 as have the sections 20, 25, and 28, and a lower cross water connection 31 joining the legs 16 and extending from the levels of the water tubes 17 of the other sections to that of the water tubes 15. When the sections 10 are placed together, the water legs 16 and the cross water tubes 15, 17, 18, and 21 of the various sections fit against the corresponding tubes of the neighboring section, the cross water connections 26 and 31 also 15 fitting against the water tubes 15 and 17 of the rearmost sections having such water tubes; but the water tubes 23 of the different sections are of less width than the sections so as to leave spaces between adjacent ones of such tubes. This provides a 20 fuel chamber 32 between the water tubes 23 and 15 and behind the firing and draft door 12, a lower flue 33 below the fuel chamber 32 and vertically between the water tubes 17 and 23 of the grate bar sections and the water tubes 17 and 26 of the baffle plate section, a vertical flue 34 in the vertical flue section 28 and horizontally between the water tubes 26 and 31, and forwardly and rearwardly carrying horizontal flues 35 and 36 between the water tubes 15 and 21 and between the water tubes 21 and 18 respectively. The rear end of the flue 36 leads into a chimney fitting 37, which 30 conveniently is removable for cleaning purposes and has a flange 38 for closing the opening between the transverse water connections 21 and 31 of the rear section 30.

Each of the various sections is provided 40 at one side near the bottom with a boss 40 for receiving a nipple 41 for connection to a side bottom header 42, and is provided at the top with a boss 43 for receiving a nipple 44 which is connected by an elbow 45 to a nipple 46 which enters a top header 47 from the side. This provides a convenient arrangement for disconnecting any section and substituting another for it without disturbing the remainder of the boiler.

50 The water tubes 23 which form the bottom of the fuel chamber are round externally, and supported on each of them is a shaker grate bar 50 mounted to turn about the axis of such tube. These grate bars 50 conveniently comprise longitudinal members at the two sides of the water tube and cross connectors 51 connecting such two longitudinal members and extending over and fitting closely against the surface of the 60 water tube 23, the cross connector at one end being provided with an upwardly extending operating arm 52 which extends up into the body of the fuel. The arms 52 of the various grate bars are pivotally connected 65 to a common operating rod 53 which ex-

tends forward somewhat beyond the front face of the furnace. There is one of these rods 53 for each half of the double furnace shown in Fig. 1. These operating rods 53 may be reciprocated in any suitable manner 70 for operating the shaker grate bars. In the arrangement shown the forward ends of these operating arms are threaded, and two nuts 54 are mounted on each one, the rod between these two nuts passing through 75 a slot 55 in an arm 56 pivoted on a bracket 57 mounted on the front face of the furnace so that the arm 56 may swing along the rod 53 and by striking the nuts 54 operate such rod and the shaker grate bars. The 80 arm 56 is also slotted to receive an eccentric 58, the two eccentrics 58 corresponding to the two rods 53 being mounted on a common shaft 59 carried in bearings 60 on the front face of the furnace. The shaft 85 59 has fixed thereon a ratchet wheel 61, and has loosely mounted thereon an arm 62 carrying a pawl 63 coöperating with such ratchet wheel. The arm 62 is connected to one end of a link 64 the other end of which 90 is mounted in a diametrical slot in a disk 65 mounted on a shaft 66 and driven through suitable gearing, such as the worm gearing 67 shown, from the shaft 68 of an electric motor 69. The slot in the disk 65 provides 95 a means for adjusting the rapidity of operation of the shaft 59, and the nuts 54 provide an adjustment for the throw of the shaker grate bars.

While in some instances the shaker grate 100 can be operated continuously, I prefer to control its operation automatically in response to the steam pressure. For this purpose, I provide in the supply circuit 70 of the motor 69 both a hand switch 71 and an 105 automatic switch 72, which are in series with each other and are conveniently mounted in a box 73. The automatic switch 72 is preferably a snap switch, which is illustrated diagrammatically, and is connected to a 110 lever 74 pivoted at 75 and operable by any suitable device responsive to steam pressure, such as the regulator 76, connected to the boiler, the lever 74 being provided with a counterweight 77 for adjusting the steam 115 pressure at which the switch 72 is opened or closed. With this control arrangement, the motor 69 is connected in circuit and operates the shaker grate when the steam pressure drops below a predetermined value, and it 120 is disconnected to stop the operation of the shaker grate when the steam pressure rises above a predetermined value. As the operation of the shaker grate tends to increase the combustion and therefore the steam production, the automatic control of the shaker grate in response to the steam pressure will 125 tend to keep the steam pressure constant.

I also provide means for producing a forced draft into the fuel chamber 82. 130

Conveniently there is a fan 80 operated by the same motor 69 which operates the shaker grate, which fan is connected by a suitable pipe 81 to the two fuel chambers 32 for the two parts of the boiler shown in Fig. 1, the lower end of the pipe 81 being bifurcated just before it leads into the front ends of said two fuel chambers. By this arrangement, the draft is automatically controlled 10 in response to the steam pressure in common with the shaking grate, so as to produce a forced draft and shake the grate when the steam pressure is down and to stop both the forced draft and the shaking of the grate 15 when the steam pressure is up, the forced draft, like the shaking of the grate, tending to increase the combustion and therefore the steam pressure. In addition, the use of the forced draft enables down-draft boilers to be 20 substituted for up-draft boilers without requiring the extra height of stack which is ordinarily necessary in order to produce the desired draft in down-draft boilers.

In operation, the fireman fills the fuel 25 chamber 32 with fuel, and thereafter ordinarily is not required to open the fuel door 12, so that the pouring out of smoke into the furnace room which usually occurs when such door is opened for stoking is prevented. 30 The flames from the under part of the bed or fuel strike the water tubes 23 and 17 and heat the water therein, and then pass by way of the flues 33, 34, 35, and 36 into the smoke stack, heating the various water tubes as 35 they pass and providing for great efficiency in transferring the heat from the hot gases to the water. The presence of water in the water tubes 23 not only serves to heat the water in the most effective parts of the 40 flames, but also tends to keep the grate bars cool so that they will not be destroyed or warped by the action of the flames. The

arms 52 project up into the bed of fuel so that they are not materially acted on by the flames. The steam pressure is maintained 45 automatically by the action of the automatic switch 72 and the parts controlled thereby, and the stoking is uniform throughout the entire fire, so that there is a uniform distribution of the air through the fire and consequently better combustion. However, the 50 rocking grate bars may also be manipulated manually when desired, by suitably reciprocating the rods 53; this may be done most conveniently by throwing out the pawl 63 55 and placing an extension on the arm 56 for operating it.

While the water tubes 23 are shown as forming integral parts of the sections 20, it is not essential that they be integral, or even 60 that they be in the planes of such sections, as my invention is intended to include the use of water tubes supporting shaker grate bars in a down-draft furnace however such water tubes and grate bars extend in the 65 furnace.

I claim as my invention:

A sectional down-draft boiler comprising a plurality of sections having water legs and cross water tubes connecting the water legs, 70 some of such sections having one of such cross water tubes below the ash pit and another between the ash pit and the fuel chamber of the boiler, and grate bars mounted on said last-named cross water bars to rock 75 thereon.

In witness whereof I have hereunto set my hand at Indianapolis, Indiana, this seventeenth day of December, A. D. one thousand nine hundred and fourteen.

HERMAN C. PROX.
